UNITED STATES PATENT OFFICE.

ROBERT NEWELL WEST, OF BALTIMORE, MARYLAND, ASSIGNOR TO ADAMS LAUNDRY MACHINERY CO., OF TROY, NEW YORK, A CORPORATION OF NEW YORK.

CLOTHES-DRIER.

SPECIFICATION forming part of Letters Patent No. 746,768, dated December 15, 1903.

Application filed March 27, 1902. Serial No. 100,298. (No model.)

To all whom it may concern:

Be it known that I, ROBERT NEWELL WEST, a citizen of the United States, residing at the city of Baltimore, State of Maryland, have invented certain new and useful Improvements in Clothes-Driers, of which the following is a specification.

My invention relates to improvements in clothes-driers of that class in which the articles to be dried are carried through a suitably-heated drying-room by an endless carrier and automatically removed from said carrier after leaving the drying-room.

In the accompanying drawings, Figure 1 is a sectional view on the line A A of Fig. 2 of a clothes-drying apparatus embodying my invention. Fig. 2 is a plan view, partially in section, on the line B B of Fig. 1. Fig. 3 is a transverse vertical sectional view on the line C C of Fig. 1. Fig. 4 is a detail perspective view of one of the clothes holders or supports, showing the manner of attaching it to the endless carrier. Fig. 5 is a detail view of a "stripper" or device for automatically removing the clothes from the carrier after they have been dried.

Referring to the drawings, 1 designates the drying-room. This may be of any suitable size and form, being preferably rectangular, as shown, and of such a height that a person may readily enter through the door 2 for the purpose of cleaning out the room or giving any necessary attention to the apparatus therein. As shown, it is preferably provided with double walls. An endless carrier is arranged to traverse the upper portion of the room 1, passing in through an inlet-opening 3 and out through a passage 4. Within the drying-room are arranged a suitable number of sprockets or guiding-wheels, about which the endless conveyer passes, said wheels being supported by transversely-extending supports 5, connected with the side walls of the drying-room by suitable brackets 6. Outside the drying-room the endless conveyer extends about similar guiding wheels or sprockets, carried by a projecting frame 7, connected at one end with the front wall of the drying-room and having its opposite end supported from the ceiling of the room in which the

apparatus is placed by means of suitable hangers 8.

As shown, I preferably employ an endless carrier consisting of two parallel endless strands 9' of wire cable, and each of the guiding-wheels above referred to consists of two members 10 10'. The guiding-wheels 10 10' are arranged in the manner shown in Fig. 2, so that the endless conveyer moves in a circuitous path through the drying-room between the inlet-passage 3 and outlet-passage 4, whereby the articles supported thereby will be thoroughly dried during a single passage through the room.

The drying-room is heated by means of suitable steam-coils. As shown, there are four of these coils, two of them, 11 12, being arranged along the side walls of the drying-room, while a third, 13, extends across the rear wall, and a fourth one, 14, extends from said rear coil forwardly between the side coils aforesaid. Steam is supplied from any suitable source to these coils, and each of them has suitable regulating or controlling valves 15, by means of which the admission of steam to any particular coil can be controlled. This is quite an important feature, because it enables either of the coils to be disconnected, if, for instance, it becomes damaged, without rendering the entire apparatus inoperative.

Within the drying-room, above the heating-coils and the endless conveyer, are arranged suitable fans 16 for causing a circulation of air within the room, which assists materially in drying the clothes. As shown, I provide two of these fans or air-circulating devices, they being carried at the lower ends of vertical shafts 17, which are suspended from above and extend through the upper wall of the drying-room. Power is supplied to said fans and to a shaft 18 for driving the endless carrier from a shaft 19, which is driven from any suitable driving mechanism through a belt 20.

The articles to be dried are supported by holders attached at suitable intervals to the cables 9' of the endless carrier. As shown in Fig. 4, each of said holders consists of a shank or stem 21, having at its lower end op-

- positely-extending arms 22 23, the free ends of which are bent upwardly, as at 24, and are provided with adjustable fingers 25, on which the articles to be dried can be hung. The 5 arms 22 23 do not extend in the same transverse plane, the former being connected with the shank or stem 21 by a bent section 26, while the arm 23 extends directly out from said shank. By this construction contact between 10 articles supported by the fingers 25 of a holder is prevented. This is of great importance, especially where varicolored articles are being dried. If the supporting-fingers 25 were directly opposite each other, the 15 articles supported thereby might contact while damp, and thereby the color of one would be transferred to the other, which is of course objectionable.
- In one face of the upper end of the stem or 20 shank 21 are provided suitable grooves for receiving the wire cables 9 9', and a clamping-block 27, having corresponding grooves, is connected with said stem by means of a bolt 28. By means of this block and bolt the 25 article holder or support can be readily attached to the endless carrier at any suitable point, and the positions of the holders or supports relative to each other can be varied as desired.
- 30 Each pair of guiding-wheels 10 10' is carried by a short vertical shaft 29, mounted in suitable ball-bearings 30 on the cross-bars 5. Said wheels 10 10' are spaced or separated slightly by suitable hubs, so that while the 35 portions of the body 21 of the article-supports enter the notches in the peripheries of said wheels the enlarged portion of said body about the connecting-bolt 28 will pass between said wheels and offer no obstruction to the movement of the conveyer.
- 40 The manner of using the apparatus as above described may be briefly stated as follows: Articles to be dried are hung upon the fingers 25 of the holders on the endless carrier as they approach the inlet-passage 3 of the 45 drying-room. They are carried in a circuitous path at a relatively slow speed through said room and exposed to the action of air heated by the steam-coils therein and circulated by the fans 16, so that before they reach the outlet-passage 4 they have become thoroughly dried. In order that the articles may be automatically removed from the endless carrier after leaving the drying-room, I have provided 50 the devices illustrated in detail in Fig. 5. Referring to this figure, 30 designates a stripper which is pivotally supported from a bracket 31 on the frame 7. This stripper consists of two downwardly-extending arms, the lower free 55 ends of each of which is provided with a passage 32 of sufficient size to permit the upturned ends 24 and fingers 25 of the holders to pass freely therethrough, but not large enough to allow the articles on said fingers to pass.
- 60 Therefore as the endless carrier is advanced the articles will be successively pushed or "stripped" from the fingers 25 and fall into

a suitable receptacle provided for them. The stripper is pivotally supported and normally held in a substantially vertical position by 70 means of a leaf-spring 33 or other suitable means in order that if for any reason one of the clothes-holders should become disarranged and not pass said stripper freely the latter can rock about its pivot, so as to clear 75 the upturned ends 24 of the holder and prevent damage to the conveyer.

To maintain the cables 9 9' of the endless conveyer in the desired taut condition, I provide tension means for adjusting the shafts 80 34 of the outer guide-wheels 10 10'. As shown most clearly in Fig. 1, these shafts are mounted in suitable bearings on the frame 7 in such manner as to be capable of a limited adjustment toward and from the drying-room. This 85 adjustment is effected by means of threaded tension-rods 35 and thumb-nuts 36. Coiled springs 37 are arranged about said tension-rods between the shafts 34 and a rear bearing 38, which springs are normally compressed, 90 so that they will automatically act to take up any slight slack in the cables that may occur. It will be seen that the two members of the stripper extend down on opposite sides of the conveyer.

95 It will be seen that by employing two cables I insure that the clothes-support will be maintained in proper position to hold the articles applied thereto in a vertical position. A single cable could not be satisfactorily employed, because of its tendency to twist when in motion, which would soon destroy the mechanism.

An opening 40 is provided at the bottom of the rear side of the drying-room, through 100 which the damp and heavy air can escape.

Having thus described my invention, what I claim as new, and desire to secure by Letters Patent, is—

1. In a drier, the combination with a drying-room, of an endless carrier mounted to travel within said room, and a series of holders each consisting of a body secured to said carrier and two laterally-projecting arms one of which extends directly out from said body 110 and the other of which is connected at its inner end with said body by a section extending substantially at right angles to the outer section of said arm and to the other arm.

115 2. In a drier, the combination with a drying-room, of an endless carrier adapted to travel within said room and consisting of two parallel cables arranged one above the other, and a series of supports for the articles to be dried secured to said cables.

120 3. In a clothes-drier, the combination with a drying-room, of an endless-cable carrier extending around suitable guide-wheels within the drying-room, and a series of holders for the articles to be dried clamped to and supported by said carrier at suitable intervals.

125 4. In a clothes-drier, the combination with a drying-room, of a horizontally-arranged endless carrier adapted to travel in said room

- and consisting of two parallel cables, and a series of holders or supports for the articles to be dried supported by and depending from said cables, each of said holders having two horizontal arms projecting laterally beyond said cables, said arms being arranged in different transverse planes. 5
5. In a drier, the combination with a drying-room, of two parallel cables arranged one above the other and mounted to move horizontally within said room, a series of holders or supports for the articles to be dried each comprising a stem or body having at its lower end oppositely-extending arms and near its upper end grooves to receive the cables, and clamping-blocks adjustably connected to said holders and coacting with the grooves therein to secure the holders in position on the cables. 10
10. In a drier, the combination with a drying-room, of an endless carrier adapted to move horizontally within the drying-room, and a holder for articles to be dried consisting of a body depending from the endless carrier and provided at its lower end with laterally-extending arms, and a finger arranged at the free end of each of said arms and extending at right angles to said arm. 15
15. In a drier, the combination of a drying-room, a series of peripherally grooved and notched wheels mounted to turn about vertical axes near the top of said room, said wheels being arranged in pairs, the members of each pair turning about the same axis, similar guide-wheels arranged outside of the drying-room, two parallel, endless, cables extending about and supported by said guide-wheels, said cables extending through suitable passages in a side wall of the drying-room, and 20 a series of depending holders or hangers for the articles to be dried secured to said cables. 25
20. In a drier, the combination of a drying-room, an endless carrier arranged to move into and from said drying-room and provided with a series of holders for articles to be dried, a stripper mounted to rock about an axis transverse to the direction of movement of the carrier, the free end of said stripper extend- 30
- ing into the path of articles supported by the carrier after leaving the drying-room, and means for normally holding the stripper in this position. 35
9. In a clothes-drier, the combination of a drying-room, an endless carrier adapted to travel within said room and provided with a series of supports for articles to be dried, said supports projecting from their connection with the carrier in a direction opposite that in which the carrier moves, and a stripper arranged to force articles rearwardly from said supports. 40
10. In a clothes-drier, the combination of a drying-room, an endless carrier arranged to travel within said room, and having a series of rearwardly-extending supports for articles to be dried, and a stripper having a slot through which said article-supports successively pass, the sides of said slot preventing the passage of articles carried by said supports. 45
11. A traveling conveyer having rearwardly-extending fingers, a stationary stripper device supported in close proximity to the path of travel of said fingers, and adapted to be encountered by said fingers in their travel. 50
12. A traveling conveyer having rearwardly-extending fingers, a stationary stripper device supported in close proximity to the path of travel of said fingers, and embodying a recess through which the fingers pass in the travel of the conveyer. 55
13. In a drying apparatus for a laundry, in combination with a traveling conveyer and a rearwardly-extending finger carried by said conveyer, a stripper device having two article-engaging members arranged on opposite sides of a vertical line extending through said finger and adapted to coöperate in engaging an article supported on said finger, substantially as set forth. 60
